UNITED STATES PATENT OFFICE.

JOSEPH KNEZIK, OF MADISON, ILLINOIS.

SAFETY LOCKING MECHANISM FOR ELEVATORS.

1,204,362.

Specification of Letters Patent.

Patented Nov. 7, 1916.

Application filed September 19, 1914. Serial No. 862,499.

To all whom it may concern:

Be it known that I, JOSEPH KNEZIK, a citizen of the United States, and a resident of Madison, in the county of Madison and 5 State of Illinois, have made certain new and useful Improvements in Safety Locking Mechanism for Elevators, of which the following is a specification.

This invention relates to a safety locking 10 mechanism for elevators.

The object of the present invention is to provide novel means for gripping the opposite sides of the vertical guides should the hoisting cable give away.

15 A further object is to accomplish the aforementioned end in a simple and novel way in which the structural features involved will be of simple design and at the same time admirably adapted for the purpose in hand.

20 A further object is to provide an elevator car with gripping means extending from the sides thereof adapted to engage and rigidly grip the opposite sides of the vertical 25 guides between which the elevator car moves.

The gripping means are adapted to engage the vertical guides at points adjacent the upper and lower extremities of the car and exert a compressive stress thereon rather 30 than tending to wedge the same apart and thus securely lock the car against movement by engagement with either one or both of the vertical guides, thus should the gripping means engage only one of the vertical guides 35 the car will be none the less securely locked as though both the vertical guides were engaged.

With the foregoing and other objects in view which will appear as the description 40 proceeds, the invention resides in the combinations and arrangements of parts and in the details of construction hereinafter described and claimed, it being understood that changes in the precise embodiment of 45 the invention herein disclosed, can be made within the scope of what is claimed without departing from the spirit of the invention.

In the drawings accompanying this specification and forming a part thereof the preferable form of my invention is illustrated in which:—

Figure 1 is a view in side elevation of an elevator car equipped with my improved 55 safety locking mechanism, Fig. 2 is a view

in front elevation of the foregoing, Fig. 3 is a sectional view taken on the line 3—3 of Fig. 2, Fig. 4 is a top plan view of the car and accompanying mechanism, portions of the car being broken away to more clearly disclose the structural features involved, 60 Fig. 5 is a fragmental view in section taken along the line 5—5 of Fig. 3, Fig. 6 is a detail view in perspective of one of the gripping arms by means of which the elevator 65 car is securely locked in position immediately upon the releasement or giving way of the elevating cables.

Referring to the drawings in which similar reference numerals designate corresponding parts throughout the several views, an elevator car C is slidably mounted between the vertical guides or runways 8 and includes the top 8', bottom 9, and sides 10. The elevator car as thus constructed is of the 70 usual form such as is utilized for freight purposes although it is to be understood that the safety locking mechanism may be utilized with equally efficient results upon passenger carrying cars. 80

Extending along the sides of the car are the outwardly facing guides 11 which include the angularly disposed faces 12 through which the holding bolts 13 extend thus rigidly securing the guides to the sides of the 85 car. The outstanding portions 12 of the guides are provided with the turned ends 14 providing the smooth travel of the car upon the vertical guides 8. The top or roof 8' of the car is provided with the aperture 90 15 which in connection with the reinforcing bushing 16 slidably receives the suspension bar or rod 17 therethrough and limits the same to a reciprocatory motion. The bar is provided with the upper cable engaging 95 end 18 to which the hoisting element or cable 19 is secured, the latter generally illustrating means for raising and lowering the car, the specific details of which, however, may be varied according to the class of service to which the elevator is to be put. 100

A beam 20 projects between and is securely fastened to the sides of the car adjacent the top and is, as illustrated in Fig. 4, formed of the two sections 21 which diverge 105 at their central portions, as at 22 and therefore define an open ended receptacle through which the suspension bar 17 extends. A casing 23 is mounted below the beam and secured thereto, the same being 110

effected by the bars 24 which are secured to the upper extremity of the casing 23 and project upwardly therefrom to form the arms 25. Suitable bolts 26 extend through the beam and arms and hold the same in rigid relation. The casing as per Fig. 3 is provided with the aperture 27 extending through its top through which the lower extremities of the suspension bar extend. The lower extremity of the suspension bar is threaded as at 28 and to which the stop block 29 is rigidly secured. A compression spring 30' is interposed between the stop block 29 and the upper end of the casing. The coiled tension spring 30 is rigidly secured, at its lower extremity to the upstanding apertured bracket 31 and at its upper extremity to the apertured block 32 the latter being rigidly secured to the suspension bar. Thus should the cable become detached or give way and the weight removed from the suspension bar the same will be instantly retracted or drawn downward by the said spring, and by the compression spring 30' which coacts therewith.

The upper extremity of the suspension bar is threaded as at 33 to which the locking nuts 34 are secured the same clamping the cross-head 35 therebetween and rigidly as well as adjustably securing it to the suspension bar. The outer extremities of the cross-head are provided with the eyes 36 through which the pins 37 extend and by means of which the links 38 are pivotally secured to the cross head. A pair of centrally arranged transversely extending shafts 39 project between and are journaled in the sides 10 of the car and are adapted to be partially rotated by the crank arms 40 which are pivotally secured to the lower extremities of the links. Rigidly secured to the outer extremities of these transverse shafts are the gripping arms 41 the same being provided with the serrated gripping surfaces 42 and as illustrated in Fig. 1 converge in a downward direction so as to engage the opposite faces of the vertical guides and be forced into wedged engagement therewith by the weight of the car. The retraction of the suspension bar by the spring 30 will thus result in the instantaneous application of the rocking or gripping arms and thus lock the car against movement in a downward direction. The cross head 35 being located above the car roof 8' and the crank arm 40 therebelow the roof is provided with the apertures 43 through which the links 38 extend and freely move.

The gripping arms 41 are located adjacent the top of the car and in order to make doubly sure the positive holding of the car a second set of gripping arms 44 are provided adjacent the car floor and are rigidly secured to, so as to be held and operated by, the shafts 45. The said shafts extend

beneath the car floor 46 and have the crank arms 47 rigidly secured thereto to which the links 48 are pivotally secured. The said links extend through the apertures 49 provided therefor in the car floor and pivotally engage the crank arms 50 carried by and rigidly secured to the shafts 39 aforementioned. Thus the partial rotation or rocking of the shafts 39 will produce a corresponding movement of the shafts 45 and effect the simultaneous operation and application of the gripping arms 41-44.

The gripping arms being arranged in pairs and upon opposite sides of the guides are adapted to wedgedly engage the same and apply only a local stress thereto. Also mention is made of the fact that should for any reason one of the vertical guides give way the hold obtained upon the other of the vertical guides will be sufficient to rigidly secure the car in position. The lower extremities of the guiding flanges 11 with which the sides of the car are provided are formed with the slots 51 therein, thus exposing the faces of the vertical guides to the gripping action of the arms 44.

I claim:

1. An apparatus of the class described comprising an elevator car, vertical guides therefor, a beam arranged between the sides of the car adjacent the top thereof, a receptacle formed by the beam, a casing arranged below the receptacle and secured to the beam and having an upper wall provided with an opening, a suspension bar slidably extending through the roof of the car and through the receptacle and into the casing, hoisting means connected with the suspension bar, a compression spring associated with the suspension bar within the casing and bearing at one end against the upper wall of the latter, a bracket rigidly supported adjacent the lower end of the receptacle, a block rigidly carried by the suspension bar above the bracket, a tension spring disposed within the receptacle and arranged between and connected to the bracket and block, a cross head adjustably carried by the suspension bar, and a plurality of gripping arms pivotally secured to the sides of the car and linkedly connected to the cross head and adapted to be rocked thereby into engagement with the said vertical guides, said gripping arms being arranged in pairs and bracing the vertical guides therebetween and adapted to engage the same at opposite sides.

2. A device of the class described including an elevator car and guides relatively to which the car moves, a beam mounted on the car and providing a receptacle, a casing secured to the beam in axial alignment with the receptacle, a suspension bar slidably extending through the receptacle and casing, a compression spring 130

associated with the suspension bar within the casing connected at one end with the bar and at its other end bearing against one end of the casing, a bracket carried by 5 the receptacle, a tension spring arranged in the receptacle connected at one end with the bracket and at its other end with the

bar, and gripping means carried by the car for engagement with the guides and actuated by the suspension bar.

JOE KNEZIK.
